UNITED STATES PATENT OFFICE.

LAWRENCE J. KRONAWITTER, OF CHICAGO, ILLINOIS.

GUARD-GATE FOR SWING-BRIDGES.

SPECIFICATION forming part of Letters Patent No. 550,105, dated November 19, 1895.

Application filed August 27, 1894. Serial No. 521,378. (No model.)

To all whom it may concern:

Be it known that I, LAWRENCE J. KRONAWITTER, a citizen of the United States, residing at Chicago, in the county of Cook and State of Illinois, have invented certain new and useful Improvements in Guard-Gates for Swing-Bridges, of which the following is a full, clear, and exact description of the invention, that will enable others to make and use the same, reference being had to the accompanying drawings, forming a part of this specification.

This invention relates to improvements in the class of guard-gates that are located at the respective ends of swing-bridges for the purpose of closing the approach thereto when the draw is open, the gates being opened and closed automatically coincident with the movement of the bridge.

Figure 1 is a broken-away elevation looking outwardly from the bridge, which is shown in section, the gates being in their open position; Fig. 2, a broken-away longitudinal section on line 2, Fig. 1, looking in the direction indicated by the arrow; Fig. 3, a broken-away elevation looking outwardly from the bridge, which is not shown, the gates being closed and the draw open; Fig. 4, a broken-away plan; Fig. 5, a diagrammatic plan of the mechanism located in the bridge approach or abutment which forms the operating connection between the ends of the bridge and gates; Fig. 6, a broken-away elevation of one of the gates in detail; Fig. 7, a vertical section on line 7, Fig. 6; and Fig. 8, a broken-away part of one of the gates in perspective.

The gates are double and have a rolling movement in a horizontal plane, meeting in the center of the bridge-approach when closed and open away from each other toward the respective sides, the tracks curving along parallel to the side railing of the footway, as illustrated in Fig. 4.

The gates comprise a series of jointed sections hinged or pivoted together, so as to conform to the curvature of the track.

A is the bridge-approach; A', the abutment; B, the bridge, and C C' the gates.

The gates consist of a number of sections 50 a, hinged together, as at a', and are supported in a suspended position from an overhead track by a number of hangers D, bolted to the

gates, as at a². The upper ends of the hangers terminate in a head a³, in which are journaled track-rollers a⁴, confined between the double-track rails D' D², supported on a number of posts a⁵. The series of rollers have a grooved periphery and engage with the adjacent track-edges of the rails. The double rails make it impossible for the rollers to become misplaced. The lower ends of the gates bear against the guide or back rail a⁶.

A sectional rack-bar b is secured to the lower ends of the gates. At one side of the approach is located a pinion-wheel b', mounted on a vertical shaft b², journaled in a bracket b³, rigidly bolted in place. At the opposite side is located a companion pinion-wheel b⁴, mounted on a shaft b⁵, journaled in bracket b⁶. These pinion-wheels are adapted to engage with the rack-bar on the gates. Sprocket-wheels d and d' are mounted on shaft b². A link-belt d² connects sprocket-wheel d with a sprocket-wheel d³, mounted on shaft d⁴. A pinion-wheel d⁵ is also mounted on shaft d⁴ 75 and is adapted, Fig. 5, to engage with the rack-bar E, secured to the end of the bridge. A link-belt d⁶ connects sprocket-wheel d' with a sprocket-wheel d⁷, Fig. 5, mounted on shaft d⁸. A pinion-wheel d⁹ is also mounted on shaft d⁸ and engages with pinion-wheel g, mounted on shaft g¹. A sprocket-wheel g² is also mounted on shaft g¹ and connects with sprocket-wheel g³, mounted on shaft b⁵, by means of link-belt g⁴. A second sprocket-wheel g⁵ is also mounted on shaft b⁵ and connects with sprocket-wheel g⁶, mounted on shaft g⁷, by link-belt g⁸. A pinion-wheel g⁹ is also mounted on shaft g⁷ and is adapted to engage with rack-bar E, secured to the bridge. 90 This system of geared and belted connections are in duplicate at each side of the bridge, so that no matter which way the bridge is moved in opening or closing a simultaneous movement is imparted to each gate. The track-rails extend straight across the width of the bridge-approach and then curve around and run back, so that the gates when open are parallel with the guard-railing of the approach.

By constructing the gates in sections they 100 conform to the curved track, and when open are entirely out of the way and do not project from each side of the bridge-approach as they would were the tracks straight.

It is obvious that a single gate may be used instead of the double one shown and opened or closed from one side only.

Having thus described my invention, what I claim as new, and desire to secure by Letters Patent, is—

In a guard-gate, the combination with the gate or gates, of a rack-bar, secured to the lower ends thereof, the pinion-wheel b' , the shaft b^2 , provided with a suitable journal-bearing, the pinion-wheel b^4 , the shaft b^5 , the sprocket-wheels d and d' , link-belt d^2 , sprocket-wheel d^3 , shaft d^4 , pinion-wheel d^5 ,

link-belt d^6 , sprocket-wheel d^7 , shaft d^8 , pinion-wheel d^9 , pinion-wheel g , shaft g' , sprocket-wheel g^2 , sprocket-wheel g^3 , link-belt g^4 , sprocket-wheel g^5 , sprocket-wheel g^6 , shaft g^7 , link-belt g^8 , pinion-wheel, and the rack-bar secured to the end of the bridge, whereby the gate or gates may be opened or closed by the movement of the bridge, substantially as set forth.

LAWRENCE J. KRONAWITTER.
